UNITED STATES PATENT OFFICE

GARLAND P. SPRINGFIELD, OF EVANSVILLE, INDIANA, ASSIGNOR OF ONE-HALF TO
O. N. ELLIATT, OF VANDERBURGH COUNTY, INDIANA

AUTOMATIC TELEPHONE DIAL ILLUMINATOR

Application filed January 7, 1931. Serial No. 507,223.

Users of telephones, particularly public telephones, experience difficulty in reading the letters and numerals on the dial of a dial system telephone, when the telephone is in a booth or unlighted location.

My object is to provide a simple and inexpensive attachment for a subscriber's telephone which may be readily attached to the column of the telephone and will be adapted 10 to co-operate with the hook of the telephone in such manner that when the receiver is removed from the hook, the device will be automatically conditioned to illuminate the dial and when the receiver is restored on the hook, 15 the illuminating device will be extinguished.

With this object in view, the invention contemplates the provision of means carried by a subscriber's dial telephone which is adapted to co-operate with the receiver-suspending 20 hook, and movable dial illuminating means co-operating therewith, whereby the dial illuminating means is latched in retracted position and the electric light carried thereby is extinguished when the receiver 25 is on the hook but, on the other hand, when the receiver is taken off of the hook, the dial illuminating means will be released and will automatically position itself to establish an electric circuit to the 30 lamp it carries so that the lamp will illuminate the dial.

The invention is susceptible of modification and I do not, therefore, limit myself to the details of construction, nor to the particular 35 dial illuminating movable device, herein-after set forth, and which is shown in the accompanying drawings, wherein:

Figure 1 is a side elevation of a subscriber's 40 dial telephone equipped with my improvements, full lines showing the normal position of the parts, and dotted lines their position when the receiver is removed from the hook and the dial is being illuminated;

Fig. 2 is a plan view of the device by itself, certain parts being in section;

Fig. 3 is a plan view of the device;

Fig. 4 is a side elevation thereof; and

Fig. 5 is a detail side elevation of the 50 device, partly in section, full lines showing the

normal position of the parts and dotted lines the dial-illuminating position thereof.

An ordinary subscriber's telephone is shown at 1 as having the receiver-holding hook 2, which appears in section, and the dial 3 by which the subscriber calls the central 55 office of exchange.

There is a clamping band 4 having sections hinged at 5 and whose parts are secured together at 6, said band carrying the operative 60 parts of the present invention.

Extending outwardly from the band 4 are arms 7 to one of which is pivoted at 8, a latch 9 which has a cam head 10 adapted to co-operate with the hook 2 in the manner indicated 65 in Figs. 1 and 2. The latch 9 has a tooth 11. A spring 12 which co-operates with the latch and with the lug 13 on the band or clamp 4, rocks the latch 9 to cause the cam head 10 to overlie the hook 2 when the receiver is on the 70 hook, as shown in Fig. 1 but said spring yields when the receiver is removed from the hook 2 so that the said hook 2 "cams" the head 10 to one side, as shown in Fig. 2. This operation of the latch 9 determines the operation 75 and use of the illuminating device which is shown, generally, at 14.

The illuminating device 14 comprises a small frame which is hinged to the arms 7 at 15; an electric bulb 16 carried by the 80 frame; switch or contact members 17 which are in circuit with the bulb 16, as shown at 18; and ratchet teeth 19 which are adapted to be engaged by the hook 11.

A spring 20 which co-operates with lugs 21 85 and 22, respectively, on the clamp 4 and the frame 14, tends to hold the frame in horizontal position, as shown in Fig. 2, with the stops 23 and 24 on the arms 7 and frame 14 in abutment with each other and the switch member 90 17 in electrical contact with a companion switch member 25 carried by one of the arms 7.

However, when the frame 14 is pressed downwardly, as shown in Fig. 1, if the receiver hook 2 is down, as when it is holding the receiver, one of the teeth 19 engages the hook 11 and is held thereby because the cam head 10 then overlies the hook 2.

When the receiver is removed from its 100

hook 2, it cams back the head 10 against the action of spring 12, disengaging the hook 11 from the tooth 19, whereupon the spring 20 snaps the illuminating device 14 to the horizontal position shown in Fig. 2. This brings the electric contacts 17 and 25 into engagement so that current from any suitable source such as an electric lamp socket or a battery, entering from the wires 26, causes 10 the lamp 16 to become illuminated and the rays therefrom pass down through the light opening 27 in the bottom of the frame 14, brilliantly illuminating the dial 3.

15 A card holder 28 may be provided on the end of the frame 14, if desired.

15 When the receiver is restored to the hook 2, the latch 9 is freed from the hook 2, whereupon the spring 12 brings the latch to the position shown in Fig. 1. The subscriber 20 may then swing down the frame 14 which will break contact between the swinging members 17 and 25 and extinguish the lamp 16. The teeth 19 ride over the hook 11 and said hook prevents the spring 20 from again 25 elevating the frame 14 until the receiver is again taken off of the hook 2.

What I claim is:

1. The combination with a subscriber's dial telephone, of a spring-actuated dial illuminator movably mounted on said telephone and adapted to automatically shift from illuminating to non-illuminating position when released, and means controlled by the receiver hook of the telephone which co-operates with 30 the dial illuminator to hold it in retracted, non-illuminating position when the hook is depressed and to release it when the hook is free, thereby enabling the dial illuminator to automatically shift to illuminating position.
- 40 2. The combination with a subscriber's dial telephone, of a clamp engaged with the column thereof, a dial illuminator hinged to the clamp and adapted to swing from ineffective to effective position, an electric bulb 45 carried by said dial illuminator, ratchet teeth carried by the dial illuminator, a spring for swinging the dial illuminator into effective position when said dial illuminator is released, electric switch members carried by the 50 clamp and by the dial illuminator adapted to establish electrical connection to the clamp when the dial illuminator is in effective position and to break said connection when it is in ineffective position, a spring-actuated 55 latch having a hook adapted to co-operate with the ratchet teeth to hold the dial illuminator in ineffective position and having a cam-head adapted to co-operate with the receiver hook of the telephone, and spring 60 means for shifting the dial illuminator to effective position when the said hook is disengaged from said ratchet teeth.

In testimony whereof I affix my signature.
